UNITED STATES PATENT OFFICE.

IRA E. STUMP, OF CLEVELAND, OHIO, ASSIGNOR TO THE ECHO HORN COMPANY,
OF CLEVELAND, OHIO, A CORPORATION OF OHIO.

AUTOMOBILE-HORN.

No. 906,332.

Specification of Letters Patent.

Patented Dec. 8, 1908.

Application filed June 17, 1907. Serial No. 379,406.

To all whom it may concern:

Be it known that I, IRA E. STUMP, a citizen of the United States, residing at Cleveland, in the county of Cuyahoga and State of Ohio, have invented certain new and useful Improvements in Automobile-Horns, of which the following is a specification.

My invention relates to improvements in automobile-horns and means for operating the same, the horn being designed to be blown by the exhaust from the motor passing through a suitable pipe or tubing connected thereto.

The horn relates more particularly to that class or type known as "divisional horns," the said horn comprising a plurality of fluid-pressure pipes provided with adjustable deflector-valves by means of which their relative pitches may be made such as to produce a chord or "chime," when sounded together.

The paramount object of the invention is to produce a simple, cheap and efficient means for admitting, regulating and controlling the operating-fluid to the horn, as well as a generally-improved horn of this class adapted to produce any desired pitch or quality of tone by manipulation of the various parts comprised in the same and adapted to produce a proper speech, blending and character of tone.

The cut-off valve shown and described but not claimed herein, is made the subject matter of a divisional application, filed February 1, 1908, S. No. 413,794.

With these ends in view, the invention consists in the novel construction, arrangement and combination of parts, hereinafter described, illustrated in the accompanying drawings, and particularly pointed out in the appended claims.

Referring to the accompanying drawings, forming a part of this specification, Figure I, is a plan view of the improved horn. Fig. II, a cross sectional view taken through line II—II, of Fig. I. Fig. III, a view of the front or outlet end of the horn. Fig. IV, a view of the rear or inlet end of the horn. Fig. V, a view of the rear or inlet end of the horn having the receiving or inlet-pipe removed. Fig. VI, a plan view, partly in section, of the rear or inlet end of the horn, and a top plan view of the improved cut-off valve and pipe connections, for controlling and admitting the operating-fluid to the horn. Fig. VII, a sectional view of the cut-off valve taken

through line VII—VII, of Fig. VI. Fig. VIII, an end view of one of the sectors of the main body portion of the horn provided with an improved adjustably-mounted sliding vibrating - valve for regulating the pitch or quality of tone produced in the respective fluid-pressure pipe formed by said sector. Fig. IX, a perspective view of the same. Fig. X, a sectional view taken through line X—X, of Fig. VI. Fig. XI, a perspective view of one of the adjustably-mounted inlet deflector-lips.

Similar characters of reference designate like parts throughout all the figures of the drawings.

The improved horn is made up of a plurality of longitudinally-extending sectors, the angled sides 1, thereof being adapted to abut against each other, and the faces 2, thereof, which make up or form the perimeter of the body portion, being convex-faced, and are, preferably, corrugated for strengthening purposes, as shown. The sectors are secured together at their front and rear ends by means of flanged heads or caps 3, and 4, respectively, mounted thereon and secured together by means of a central longitudinally-extending rod or bolt 5, threaded at its front end and provided with a nut 6, and having an eye or cross-opening 7, taking over a cross-pin 8, said cross-pin having its ends secured in the walls of the receiving or inlet-pipe 9. The longitudinally-extending sectors form a plurality of longitudinally-extending fluid - pressure pipes 10, open at their front or outlet ends, the cap 3, being provided with vent-openings and recesses 11, as shown. The receiving or inlet-pipe 9, communicates with the fluid-pressure pipes, 10, by means of inlet slots or recesses 12, formed between the face of the cap or head 4, and the end 13, of triangular shape in cross section, of the receiving or inlet-pipe 9, and inlet-openings or slots 14, are formed in the head or cap 4, adjacent to and outside of said inlet-slots or recesses 12. The size of the several inlet-openings or slots 14, is adapted to be increased or decreased by means of slidably and adjustably-mounted lips or tongue-pieces 15, secured to the cap or head 4, by means of screws 16, passing through slots 17, and taking into threaded openings of the head or cap 4. The several inlet-openings or slots 14, are separated from each other by means of plates 18, having rear-

wardly and outwardly-extending deflector-wings or flanges 19, said wings or flanges 19, extending substantially flush with the ends of said openings or slots 14, and the plates 18, 5 being secured to the head or cap 4, by means of screws 20. The ends of the angular projecting portions or corners 13^a, of the triangular-shaped end 13, of the inlet-pipe 9, abut against the plates 18, leaving the slots 10 12, intermediate said plates and corresponding in depth to the thickness of said plates.

As a means of modifying the pitch produced at the several inlet-openings communicating with the respective fluid-pressure pipes, said wings or flanges 19, may be bent inwardly and above said inlet-openings or slots 14, at an acute angle until the desired pitch is secured. As a further means of modifying the pitch, above referred to, a deflector-lip or plate 21, may be mounted and interposed between the wings or flanges 19, and at the rear of said inlet-openings or slots 14, (see Figs. I and IV), the base portion 22, thereof, being slidably and adjustably-mounted upon the inlet-pipe 9, by means of a screw 23, passing through a slot 24. If desired, the deflector-wings or flanges 19, and deflector-lips 21, may be made integral with the inlet-pipe 9; and the wings 19, and deflector-lips 21, interposed between said wings might also be made integral with each other. As the operating-fluid passes through the inlet-pipe 9, it impinges against the cap or head 4, and is directed outwardly through the slots or recesses 12, and over and against the lips or tongue-pieces 15, of the inlet-openings or slots 14, communicating with the several fluid-pressure pipes 10, and thereby sounding the horn in a well known manner.

40 As a further means of securing the desired pitch of tone arising in the several fluid-pressure pipes, and, more particularly, by which their relative pitches may be made such as to produce a chord or "chime," when sounded together, a valve is mounted in each of the longitudinally-extending sectors, preferably near the front or discharge ends thereof, said valve consisting of a base portion 25, and a depending vibrating plate 26, adapted 45 to vibrate crosswise in the pipe in which it is mounted, said base portion 25, being slidably-secured to the inner side of the convex-face 2, by means of an adjusting-nut 27, passing through said face 2, and through a slot 28. The depending-plate 26, may be of any suitable and convenient form and by positioning the several valves in the several fluid-pressure pipes, at different relative positions a perfect chord or "chime" may 55 be produced.

60 The improved means for operating the horn, consists of an exhaust-pipe 29, leading from the motor, and provided with a T-pipe-fitting 30, provided with a cylindrical-shaped valve-body or housing 31. A reduced lateral

70 pipe or boss 32, leads from the valve-body 31, and is connected to the inlet-pipe 9, of the horn by means of a connecting-pipe 33. The ends of the cylindrical valve-body 31, are closed by means of disk bearing-plates or heads 34, provided with central bearing-openings carrying the ends of a rotatably-mounted valve-bearing-shaft 35. The valve, proper, consists of an arm 36, terminating at one end in a hub or bearing-head 36^a, secured to the shaft 35, by means of a screw 37, and at the other in a concavo-convex-shaped disk-bearing-head 38, conforming to the adjacent inner cylindrical wall of the valve-body 31, said head 38, normally closing the lateral inlet-opening 32^a, and being of sufficient size to close the main outlet-opening 29^a, of the exhaust-pipe 29, when operated by the means hereinafter described. One end of the shaft 35, is intersected by 75 means of an operating-arm or lever 39, adjustably-mounted therein by means of a set-screw 40, and the free end of said lever 39, is provided with a spring 41, normally closing the inlet-opening 32^a, as shown in Fig. 90 VI, and is provided with a cable 42, designed to operate against the resistance of said spring, said cable being connected to a foot-lever, or other suitable and convenient operating-device (not shown), by means of which the valve, proper, may be moved to wholly or partially close the outlet opening 29^a, and to correspondingly open the inlet-opening 32^a, whereby more or less of the operating-fluid may be diverted through the connecting-pipe 33, leading to inlet-pipe 9, of the horn whereby the latter is operated as desired and whereby to regulate the quantity and pressure of the operating-fluid.

75 As a means of providing against an over-supply or pressure of operating-fluid in the inlet-pipe 9, whereby too high a pitch of tone would be produced, an escape-valve is formed at the side of said inlet-pipe 9, consisting of a vent-opening 43, normally closed by a disk-valve-plate 44, carried upon the lower end of a vertically-arranged movable bar or pin 45, having its upper end passing through a guide-opening of the upper end of a guide-bracket or housing 46, the base ends 115 of which are mounted on the inlet pipe 9, by means of screws 47. A spring 48, takes over the pin 45, and under the upper end of the guide-bracket, whereby to normally close the vent-opening 43, the pressure of the 120 valve-plate being regulated by means of an adjusting-nut 49, threaded upon the lower end of the pin 45.

From the foregoing description, taken in connection with the accompanying drawings, 125 the operation and advantages of my invention will be readily understood.

Having thus described my invention, without having attempted to set forth all the forms in which it may be made, or all the 130

medes of its use, I declare that what I claim and desire to secure by Letters Patent, is,—

1. In a horn, a sounding element provided with a vibrating-valve consisting of a base-plate slidably and adjustably-mounted and a depending vibrating-plate integral with said base-plate and extending crosswise in said sounding element.
2. In a horn, a longitudinally-divided horn body, an inlet-pipe, inlet-slots leading from said inlet-pipe to said horn body, and valves mounted in said horn body, each of said valves comprising an adjustably-mounted base-plate carrying a vibrating-plate extending crosswise in said horn body.
3. In a horn, a plurality of fluid-pressure pipes, a common inlet-pipe, inlet-slots leading from said inlet pipe to said fluid-pressure pipes, plates mounted intermediate said inlet-slots and provided with wings at the sides of said inlet-slots, and tongue-pieces and deflector-lips adjustably-mounted above and at the rear of said inlet-slots, respectively, and intermediate said wings.
4. A horn, comprising a horn body made up of a plurality of fluid-pressure pipes, a rear head provided with an inlet-pipe and inlet-slots leading from said inlet-pipe to said fluid-pressure pipes, plates mounted on said head intermediate said inlet-slots and provided with wings at the ends of said inlet-slots and extending rearwardly at right angles to said head, and tongue-pieces adjustably-mounted at the rear of said inlet-slots and intermediate said wings.
5. A horn comprising a plurality of fluid-pressure pipes, a head secured thereto and provided with inlet-slots leading to said pipes, an inlet-pipe secured to said head and leading to said inlet-slots, plates secured to said head and provided with wings extending rearwardly at the ends of said inlet-slots and at right angles to said head, and deflector-

lip intermediate said wings and at the rear of said inlet-slots.

6. In a horn, a head carrying a plurality of fluid-pressure pipes and provided with a plurality of inlet openings communicating therewith, an inlet-pipe having its end provided with inlet-slots directing the operating fluid to said inlet-openings of said head and carrying a plurality of radially-extending deflector-wings secured to said head between said inlet-openings and extending at right angles thereto, and deflector-lips carried by said inlet-pipe between said deflector-wings.

7. A horn, comprising a plurality of fluid-pressure pipes, a head secured thereto and provided with inlet-slots leading to said pipes, a common inlet-pipe secured to said head and carrying a plurality of deflector-lips at the rear of said inlet-slots, and deflector-wings extending from said inlet-pipe on each side of said deflector-lips and separating said inlet-slots of the head.

8. A horn, comprising a plurality of fluid-pressure pipes, a head secured thereto and provided with inlet-openings leading to said pipes, an inlet-pipe secured to said head and communicating with said pipes by means of inlet-slots in its end directing the operating fluid to said inlet-openings of the head adjacent to and outside of said inlet-slots, a plurality of deflector-lips carried by said inlet-pipe at the rear of said inlet-slots and openings, and deflector-wings on said head between said inlet-openings and extending rearwardly at right angles from said head between said inlet-openings and on each side of said deflector-lips.

In testimony whereof I have affixed my signature, in presence of two witnesses.

IRA E. STUMP.
